(57) **CLAIM**

We claim, the ornamental design for a steerable catheter handle, as shown and described.

DESCRIPTION

FIG. 1 is a front perspective view of a steerable catheter handle;

FIG. 2 is a left side elevational view of the steerable catheter handle;

FIG. 3 is a top plan view of the steerable catheter handle;

FIG. 4 is a right side elevational view of the steerable catheter handle;

FIG. 5 is a bottom plan view of the steerable catheter handle;

FIG. 6 is a front elevational view of the steerable catheter handle;

FIG. 7 is a rear elevational view of the steerable catheter handle; and,

FIG. 8 is a rear perspective view of the steerable catheter handle.

The broken lines in the drawings illustrate portions of a steerable catheter handle and form no part of the claimed design.

1 Claim, 7 Drawing Sheets
